DOLL HEAD AND METHOD OF MAKING IT

Frank D. Moos, New York, N. Y.

Application September 19, 1947, Serial No. 775,123

2 Claims. (Cl. 46—164)

1

This invention relates to dolls' heads, and particularly to improvements in the method of making such heads and the product thereof. Dolls' heads are manufactured from a great variety of materials. Those which are most lifelike have natural hair in the form of a wig which is glued or otherwise fastened to the skull made of any suitable material and molded or shaped to the desired contour with the features of the face formed thereon and colored by painting or otherwise. The manufacture of such small wigs is a relatively expensive operation. The wigs are delicate and are easily destroyed. Consequently such dolls are costly and are not completely satisfactory.

It is the object of the present invention to provide a method of producing dolls' heads and a product which may be made quite lifelike and interesting.

A further object of the invention is the production of a doll's head in which the face and hair are composed of the same material, that is, a natural skin, whereby the cost of the head is substantially lower and a more satisfactory and durable product is made available.

Other objects and advantages of the invention will be apparent as it is better understood by reference to the following specification and the accompanying drawing, in which

Fig. 1 is an elevation illustrating a doll's head manufactured in accordance with the present invention;

Fig. 2 is a front elevation of the base upon which the skin is molded as hereinafter described;

Fig. 3 is a rear elevation of the base;

Fig. 4 is an elevation of a mold which is employed in forming the facial portion of the head; and

Fig. 5 represents a section of animal skin adapted to be applied to the base.

In carrying out the present invention, I employ furred skins of any suitable animal. The fur is selected to provide hair of the preferred length and of natural appearance. The hair is removed from that portion of the fur which is to form the face and neck of the head, and the skin is molded over a suitable base shaped in the form of a skull with the features of the face thereon. Preferably a recessed mold is employed to ensure application of the skin tightly and in the proper contours. The base is provided with slots on the cranial portion, and the skin is cut so that the edges thereof can be tucked into the slots and secured with a suitable adhesive. The por-

tion of the skin having the natural hair attached provides the hair on the doll's head. It may be dyed either before or after application. The skin on the facial portion can be painted or otherwise colored to provide a suitable complexion.

The dolls' heads made in accordance with my invention may have any desired features such as those of a baby or child. They may be made also to represent realistically actors and actresses and other public personages of the past or present. Because of the use of animal skin to cover the base, the features may be made quite lifelike and the hair may be formed and dressed in accordance with the style commonly adopted by the particular individual represented by the doll.

The use of an animal skin as described affords a doll's head which is very durable. The hair is, of course, tightly held by the skin, and it cannot be removed without substantial destruction of the head. Dolls' heads constructed in accordance with my invention are extremely lifelike and attractive and much more durable and less costly than dolls' heads as heretofore constructed.

Referring to the drawing, 5 indicates a head having a facial portion 6 with the usual features and hair 7 on the cranial portion. The hair, as indicated, is natural hair of a skin, the hair having been removed from that portion of the skin which covers the facial part 6 of the head.

In the manufacture of such a doll's head, I first provide a base 8. It may be made of plaster, papier-mâché, plastic or any other moldable material shaped in the form of a skull, with the facial features 9 appearing thereon. Preferably the base is hollow, as indicated by the dotted line 10, but it may be solid. At the rear of the skull portion, I provide, as shown in Fig. 3, diagonal slots 11 and a central slot 12. The exact form and arrangement of the slots is not essential. They are intended to permit drawing of the skin over the rounded portion of the skull, so that the edges may be tucked into the slots and secured by any suitable adhesive.

I prepare a strip 13 of suitable size, consisting of a furred skin. The part 14 thereof is denuded of hair by cutting it away. Thereafter, any of the well known depilatories may be employed to remove the remainder of the hair, leaving the skin clean and soft. The hair remains on the part 15, which is to cover the skull portion. A part of the skin may be cut away, as indicated at 16, in order that it may be drawn tightly around the skull without wrinkles.

A mold 17 is provided with the facial features 18 formed in intaglio. The mold should be sufficiently larger than the dimensions of the base 8, so that the skin may be interposed. A suitable adhesive is applied to the base 8, and the base is forced into the mold 17 with the bare portion 14 of the skin in proper position so that it will cover the facial part of the base 8. The remainder of the skin is then drawn over the cranial portion of the base 8 and secured with adhesive, the edges of the skin being tucked into the slots 11 and 12 and secured therein. The skin is worked down over the neck portion 19 and secured by adhesive. When the latter is dried, the face portion 6 may be withdrawn from the mold. The skin will be found to adhere closely to the features of the face portion. The hair line may be modified, if necessary, by removal of any excess hair. The face portion may be then painted or otherwise colored to afford a satisfactory complexion. After dressing the hair, in the desired style, the doll's head is complete. It may be secured to a body of any form, such as are commonly provided in the manufacture of dolls.

Various changes may be made in the procedure as described and in the product without departing from the invention or sacrificing the advantages thereof.

I claim:

1. The method of making dolls' heads which comprises forming an artificial base in the shape of a skull with the facial features thereon, covering the base with an animal skin from a portion of which the hair has been removed so that the portion from which the hair has been removed covers the facial features and the portion having the natural hair thereon covers the cranial portion of the base, distorting the portion of the

skin extending over the facial features to cause it to conform to the irregularities of the facial features, and securing the skin to the base with the irregularities of the distorted portion of the skin conforming to and tightly adhering to corresponding irregularities of the facial features.

2. A doll's head comprising an artificial base having a facial portion and a cranial portion having slots in the outer surface thereof, an animal skin covering said portions, the skin covering the facial portion being free from hair and molded to the facial form of the base, and the skin covering the cranial portion being a continuation of the skin covering the facial portion and having the natural hair thereon, the edges of the portions of the skin covering the cranial portion being secured within said slots.
